UNITED STATES PATENT OFFICE.

ERNEST KELLERSTRASS, OF EXCELSIOR SPRINGS, MISSOURI.

CHURN.

SPECIFICATION forming part of Letters Patent No. 430,654, dated June 24, 1890.

Application filed March 18, 1890. Serial No. 344,309. (No model.)

To all whom it may concern:

Be it known that I, ERNEST KELLERSTRASS, of Excelsior Springs, Clay county, Missouri, have invented certain new and useful Improvements in Churns, of which the following is a full, clear, and exact description, reference being had to the accompanying drawings, forming a part hereof.

My invention relates to churning butter; and it consists in the following combination of different parts, hereinafter more fully described, and set forth in the accompanying drawings, in which—

Figure 1 is a perspective view of the invention. Fig. 2 is a longitudinal sectional view. Fig. 3 is a cross-sectional view. Fig. 4 is a detail view showing the construction of the upper portion of the perpendicular shaft. Fig. 5 is a detail view showing the spring-arm and the shaft J drawn up and out of their operative position.

It will be seen at Fig. 1 in constructing my invention I use a square vessel so constructed that it will hold milk or cream without leaking. In this particular case I use a vessel made square, with a molding around the top, forming a depending flange around the same. Then I make my lid in two pieces, making one piece about as large again as the other. The lid is then dropped in position on the churn, and the small buttons attached to the molding, forming the depending flange with the top of the churn, are turned around, extending over the edges of the lid, holding it in position. On the smaller piece of the lid I use a knob to remove that portion at any time during the churning process, so that the cream or milk may be seen at any stage of churning. Two uprights D D are rigidly secured to the larger portion of the lid. On the upper ends of said uprights is mounted a shaft carrying a gear-wheel G, attached thereto, said gear-wheel meshing with a cog-wheel L, by means of which the dasher-shaft, extending down to the bottom of the churn, is rapidly revolved. It will be seen in Fig. 5 that in order to detach the lid from the shaft I have provided a longitudinal sleeve. The upper portion of the shaft, which is secured to the small cog-wheel, is provided with a loop made of a suitable-sized piece of wire, the top end of which passes

through a perforation made in the shaft, and suitably riveted to hold it in position, at the same time it works loosely. The bottom end of the spring-arm when in position is inserted in a perforation at the lower portion of the sleeve, holding the machinery and lower portion of the main shaft together, the shaft resting over a pivot at the bottom of the churn. I then take the portion of the lid which has the machinery mounted thereon. The top portion of the shaft is then inserted in the sleeve, drops down until the top portion of the wire lever is in the slot at the top of sleeve, and then before the operation of churning is commenced the churn is filled sufficiently full of cream. The bottom portion of the spring-arm is then sprung into a perforation, (seen at the bottom end of the sleeve,) which holds it firmly in position during the churning operation.

In Fig. 1, G is the gear-wheel. F is the horizontal shaft; H, the crank; K, the journal end of upright shaft; L, small cog-wheel; d, the extended arm in connection with the portion holding the small cog-wheel in position; D D, uprights; e, two extended lugs in which is a small lag-pulley holding large cog-wheel in position.

i is a slot in the upper end of the sleeve I, in which lever M drops when in position; J, the portion of shaft which drops into sleeve in a perforation in the lower end of the sleeve in which the right-angled lower end of spring-arm is inserted. B is the large portion of the churn-top.

C is the small portion of the top; c, knob; b, buttons, which hold the top in position. p is a metallic flange rigidly secured to the under side of the churn-top, through which shaft passes.

n is a rivet, which holds the lower portions of the sleeve to the main shaft; N, the main shaft; O O, the dashers, which are made of any suitable length, V shape in cross-section, and attached to the main shaft in a spiral-like form.

P is a pivot extending through the bottom of the churn, forming a bearing for the dasher-shaft.

Having thus fully described my invention, what I claim, and desire protection in by Letters Patent, is—

In a churn, the main shaft having an extension I, provided with a slot *i* and recess *m*, the shaft K, the sleeve J, secured around the shaft K, the spring-arm secured to said 5 sleeve and shaft and engaging slot *i* and recess *m*, the cog-wheel L, secured to the shaft K and meshing with a gear-wheel, a small idle-wheel, which holds the gear-wheel in position, uprights D D and projections *d* and *c* on the 10 same, a suitable bearing for the gear-wheel,

the said shaft K, and sleeve J, located inside of the extension I of the main shaft, substantially as described.

In testimony whereof I affix my signature in presence of two witnesses.

ERNEST KELLERSTRASS.
